UNITED STATES PATENT OFFICE.

JOHN L. WOOLLEY, OF GOLDEN, COLORADO.

POTATO-HARVESTER.

SPECIFICATION forming part of Letters Patent No. 425,922, dated April 15, 1890.

Application filed May 14, 1888. Serial No. 273,900. (No model.)

To all whom it may concern:

Be it known that I, JOHN L. WOOLLEY, of Golden, in the county of Jefferson and State of Colorado, have invented a certain new and useful Improvement in Potato-Harvesters, of which the following is a full, clear, and exact description, reference being had to the accompanying drawings, forming part of this specification, and in which—

10 Figure I is a side elevation of my improved device, showing it out of gear and in the position it occupies when turning around or when it is being moved from place to place. Fig. II is a side view showing the parts in 15 using position. Fig. III is a top view. Fig. IV is a detail perspective view of the elevator-carrier. Fig. V is an enlarged perspective view of the shovel. Fig. VI is a detail view, and Fig. VII is a perspective view of 20 the weed-catcher. Fig. VIII is a side view of the shovel and weed-catcher.

My invention relates to a machine for digging and gathering potatoes; and my invention consists in features of novelty hereinafter fully described, and pointed out in the 25 claims.

Referring to the drawings, 1 represents a frame of rectangular or other shape, and which is mounted on wheels 2 and caster-wheels 3. The wheels 2 turn on an axle or cross-piece 4, and to one of the wheels is secured a cog-wheel 5, with which meshes a pinion 6 on a shaft 7, journaled in boxes 8, supported by the frame 1 at one side of the 30 machine, and on the shaft 7 is a chain-wheel 9, over which passes a chain-belt 10 that also passes over another chain-wheel 11 on a shaft 12, journaled in the upper end of the elevator 13. On the shaft 12 are wheels 14, over 35 which the carrier 15 of the elevator passes at the upper end of the elevator. At the lower end of the elevator are wheels 16, over which the carrier passes at the lower end of the elevator. The carrier is composed of chains 17, (see Fig. IV,) connected by rods 18 and buckets 19, said buckets having inwardly-projecting ears 19^a, secured to inwardly-projecting lugs 17^a on some of the links of the chains, which are made to flare outward from the 40 chains 17, as shown in Fig. IV. This construction forms an open carrier, through which dirt may readily pass, but which is

sufficiently close to prevent the passage of the potatoes.

20 represents a horizontal shovel located in front of the lower end of the elevator 13, and which delivers the potatoes onto the elevator. The construction of the shovel is shown best in Fig. V, it consisting of a blade 21 and an upwardly-inclined heel 22. The blade enters 25 the ground, (when the machine is at work,) as shown in Fig. II, and the potatoes and dirt pass up over the heel and are delivered into the buckets of the elevator.

As the machine is moved forward the elevator turns in the direction indicated by the arrows in Fig. II, and the potatoes are carried up and delivered into a hopper or spout 23, located at the rear of the machine, and which may discharge into a sack or other receptacle, if desired. As the potatoes are thus carried up and discharged into the hopper, the dirt sifts through between the rods 18 and falls upon the ground.

The heel of the shovel has side pieces 24 75 perforated at the corners, as shown at 25, to receive rivets or pins 26, by which links 27 28 are secured to the shovel at their lower ends. The upper ends of the links 27 are connected at 29 to cranks 30 on a rock-shaft 31, journaled 80 in boxes 32 secured to the frame of the machine. The links 27 are secured to the front of the shovel, and in addition to these links 32 are also secured to the front of the shovel, and which are connected at their upper ends 85 to the frame of the machine by means of short links 33. The lower ends of the links 32 are connected to the shovel by the same rivets or bolts that connect the links 27 to the shovel. The links 28 are made in two parts 90 with a joint 40, as shown in Fig. VI. The upper ends of the upper parts are connected to cranks 41 on a rock-shaft 42, journaled in boxes 43 secured to the seat-support 44.

45 represents the seat. 46 represents a lever 95 on the shaft 42, and 47 represents a lever on the shaft 31.

48 represents a frame which fits and slides on the frame 1. To this frame 48, the shaft 7 of the gear-wheel 9 is secured by the boxes 8 100 of the shaft. The frame 48 is held on the frame 1 by means of plates or brackets 50. (See Fig. III.)

The elevator is connected to the frame 1 by

means of strips 51, which are grooved to receive the edges of the elevator. (See dotted lines, Fig. III.) The frame 48 is connected to the elevator by means of an arm 53, pivoted 5 at 54 to the frame and at 55 to the elevator. The grooved strips 51 are slotted, as shown at 56, Figs. I and II, for the passage of the pin 57 that connects the upper ends of the links 53 to the elevator. As the frame 48 is moved 10 in the direction indicated by the arrow, Fig. II, from the position shown in Fig. II to the position shown in Fig. I, the pinion 6 is carried out of engagement with the cog-wheel 5 and the elevator, together with the parts attached to it, are raised from the position shown in Fig. II to the position shown in Fig. I. This is done when a corner is to be turned, or when the machine is to be placed in position for transportation. This movement of 20 the parts is accomplished by the lever 47, the shaft 31 having a crank 60 connected by means of a link 61 to the sliding frame 48. It will thus be seen that when the lever is moved in the direction indicated by the arrow in Fig. II the frame 48 will be moved together with the elevator, as described. This movement of the lever 47 also lifts the shovel from the ground through means of the connecting-links 25 27 and cranks 39. As the shovel is raised, the links 32 33 fold up, as shown in Fig. I, and when the parts are lowered again these links prevent the shovel from entering the ground too far.

The object of the links 28 is to raise and 30 lower the heel of the shovel, and this is done by moving the lever 46 in the desired direction.

The joints of the link 48 are made to move 35 in a vertical position by the connecting-pins 40 at 40, working in keepers or brackets 65.

70 represents a weed-catcher of the shape shown in Fig. VII, which is secured to the sides 24 of the shovel 20, as shown by dotted lines in Fig. V. It has holes 71 to receive

bolts that also pass through holes 72 in the 45 sides of the shovel. It may be adjusted up or down, as desired, by moving the bolts to different holes. It catches and deflects the weeds from the shovel.

I claim as my invention—

1. In a potato-harvester, the combination of a shovel, elevator, and means for operating the elevator, the elevator being composed of side chains, some of the links of which are provided with inwardly-projecting lugs, connecting-rods between the chains and buckets 19 separate from the connecting-rods having inwardly-projecting ears secured to the lugs of said chains, substantially as set forth.

2. In a potato-harvester, the combination of a shovel, elevator, means for turning the elevator, and shovel simultaneously, consisting, essentially, of a sliding frame and independent links connected with the elevator and shovel, 65 respectively, and all leading to suitable operating devices having connection with the sliding frame, substantially as and for the purpose set forth.

3. In a potato-harvester, the combination of the shovel, elevator, means for turning the elevator, and means for lifting the elevator and shovel simultaneously, said means consisting of a sliding frame to which the elevator is connected, a rock-shaft, connection between the rock-shaft and sliding frame, a lever on the rock-shaft, and links connecting the shovel to the rock-shaft, substantially as and for the purpose set forth.

4. In a potato-harvester, the combination of the shovel having sides 24 and a weed-catcher having a broad guard-surface adjustably secured to the sides of the shovel, substantially as and for the purpose set forth.

JOHN L. WOOLLEY.

In presence of—

JOSEPH MANN,

D. E. HARRISON.
